METHOD AND INSTRUMENT FOR ELECTRO-SURGICAL TREATMENT OF TISSUE

Reinhold H. Wappler, Yonkers, and Frederick Charles Wappler, New York, N. Y.; said Frederick C. Wappler administrator of said Reinhold H. Wappler, deceased

Application November 22, 1932, Serial No. 643,846

20 Claims. (Cl. 174—89)

Our present invention relates generally to electro-surgery, and has particular reference to an improved type of electrodisic instrument, and, coordinately, to an improved method of treating 5 tissue.

It is a general object of our present invention to provide an improved electro-surgical instrument of the character in which means are provided for conducting or directing high-frequency 10 electric current to interior portions of the human body for the purpose of subjecting tissue to the unique actions of such current. Our present instrument provides a novel and improved assembly of operative parts whereby an electrode or 15 electrodes may be more efficiently and controllably manipulated for the purpose of effecting certain desired treatments of tissue.

A more particular object of our invention lies in providing an improved instrument for effecting coagulation, cutting, or other destruction, shrinkage, or treatment of tissue in relatively inaccessible places; also for permitting improved and more controllable coagulation and/or cutting and/or treatment of neoplastic growths 20 in general; also for effecting removal or severance of growths and adhesions in an improved and expeditious manner.

It is vitally important, in the treatment of most interior growths, adhesions, and the like, 25 that assured hemostasis be effected, for the reason, among others, that interior hemorrhage is all too frequently disastrous. In the cutting of adhesions or growths, for example, it is extremely important that the resultant stumps be retained under proper and visible control until 30 after the surgeon or operator has made certain that complete hemostasis has been achieved.

It is a feature of our present instrument to provide a unitary, compact electrodisic instrument 35 which permits a wide variety of electro-surgical procedures and/or treatments to be carried out with great facility and with an improved simplicity of control and manipulation. Our instrument permits operations to be performed 40 under conditions which enable the operator to proceed in an unhurried and careful manner, with maximum safety and provision for thorough visibility, examination, and treatment, and with a minimum of danger, especially so far as 45 uncontrollable hemorrhage is concerned.

A particular feature of our invention lies in providing an instrument in which a single control mechanism may be employed to effect a variety of movements and manipulations of one or 50 more electrode elements. Briefly, our invention

embodies the usual elongated stem insertable through an endoscopic tube, a movable member pivotally associated with the forward end of the stem, a mechanism for controlling the movements of such member, and an electrode articulated to the stem and to the movable member in such a manner that movements of the pivoted member will compel corresponding and responsive movements of the electrode.

In a preferred embodiment of our invention, 10 the movable member is constructed in the form of a two-armed jaw adapted to cooperate with a similar complementary jaw of stationary character. Between the arms of the movable jaw we arrange a means for articulating the free 15 forward end of a wire electrode which is in pivotal association with the stem at the rear of the jaw. In accordance with this arrangement of parts, a single control means will swing the movable jaw toward and away from the stationary 20 jaw, and will simultaneously constrain the wire electrode to move in a similar and corresponding manner. The uses to which these several elements may be put are quite varied, as will be pointed out hereinafter, and permit a variety of 25 operative procedures to be carried out with enhanced facility, reliability, and ease. For example, where the electrode wire is provided with a portion extending forwardly through the arms 30 of the movable jaw, the instrument is admirably suited for effecting a novel type of severance of an adhesion or growth, under conditions which automatically couple a cutting procedure with a clamping action, which engages the resultant 35 stump or stumps, thereby holding the latter for examination and possible further treatment before the operation is entirely completed. This 40 procedure constitutes by itself an important and independent object of our invention.

In a preferred form of instrument, the stationary jaw hereinbefore referred to is constructed and arranged to serve as a second electrode, insulated from the movable wire electrode hereinbefore referred to, whereby the instrument is 45 readily adapted for a further variety of useful purposes and modes of procedure.

A further feature of our invention lies in constructing the instrument in such a manner that a variety of wire electrodes may be removably and selectively associated therewith, thereby 50 combining a wide number of capabilities in a single compact instrument and facilitating disassembly, sterilization, etc.

A further general object is to provide means 55 for assuring continuous and fully illuminated

vision of the operative parts and of the tissue portions being treated, including means for exhausting the area of operation of such fumes as may be generated in the vicinity of the telescopic objective.

We achieve the foregoing objects, and such other objects as may hereinafter appear or be pointed out, in the manner illustratively exemplified in the accompanying drawings, wherein—

10 Figure 1 is a perspective view of an instrument embodying the features of our present invention;

15 Figure 2 is an enlarged longitudinal cross-section through the instrument of Figure 1, with certain portions omitted for the sake of clearness;

Figure 3 is a plan view, partly in section, taken substantially along the line 3—3 of Figure 2, with certain parts omitted for the sake of clearness;

20 Figure 4 is an enlarged cross-sectional view taken substantially along the line 4—4 of Figure 1;

Figure 5 is a cross-sectional view taken substantially along the line 5—5 of Figure 2;

25 Figure 6 is a longitudinal side view similar to the left end of Figure 2, showing a modified type of electrode in association with the instrument;

Figure 7 is a side view of the electrode of Figures 1—5, shown by itself;

30 Figure 8 is a view similar to Figure 7, illustrating the electrode of Figure 6 by itself;

Figure 9 is a side view of the forward end of the instrument of Figure 1, showing a step in one mode of use;

35 Figure 10 is a diagrammatic cross-sectional view taken substantially along the line 10—10 of Figure 9;

Figure 11 is a view similar to Figure 9, showing a subsequent step in the procedure;

40 Figure 12 is a diagrammatic cross-sectional view taken substantially along the line 12—12 of Figure 11;

Figure 13 is a side view of the forward end of the instrument of Figure 6, showing one manner of use; and

45 Figure 14 is a view similar to Figure 13, showing an adjusted relationship of parts during a further procedure.

The endoscopic tube 20 terminates at its rear end in the flange 21 and in the attachment sleeve or neck 22. The neck 22 carries the irrigation outlet 23 and also suitable mechanism such as the clamp 24 for facilitating association with the tube 20 of the interior removable assembly.

50 The operative assembly consists of the usual plug 25 whose forward portion (not shown in Figures 2 and 3) is slightly tapered and is adapted to fit snugly into the neck 22. The plug 25 carries a forked member adapted to engage in a suitable manner with the clamping arrangement 24, and is also provided with an electric binding post 26 which is mounted in uninsulated relationship so that all of the parts not specifically insulated from the binding post 26 or the plug 25 are in electrical contact therewith.

65 Extending rearwardly from the plug 25 is the supporting arm 27 terminating in its rear end in a bearing 28 and a suitable clamp 29, the bearing 28 and clamp 29 being adapted to engage and secure the rear end of a suitable telescopic device 30. The latter is preferably of the character illustrated and described in United States Letters Patent No. 1,680,491, and consists of an eyepiece 31, suitable terminal bands 32 for establishing electrical connection with the forward illuminating lamp 33, and an objective lens 34 arranged

behind the lamp 33 and commanding an obliquely forward field of vision.

The arm 27 also carries the insulated terminal block 35, secured by the stud 36 and provided with the insulated binding post 37.

Secured to the plug 25 and projecting forwardly therefrom is the elongated stem 38 provided with the upper guide channel or tube 39, the lower guide channel or tube 40, and the lateral guide tubes 41. The telescope 33 is adapted 10 to be accommodated in the upper channel or tube 39, and it will be understood that the plug 25 and the block 35 are provided with suitable bores through which this telescope may slidably extend.

15 At the forward end of the stem 38 we mount the stationary jaw 42 which consists preferably of two spaced parallel arms substantially aligned with the axis of the stem 38. These arms preferably join at the forward end so that the jaw 20 is substantially U-shaped when viewed in a horizontal plane.

Pivoted to the rear of the fixed jaw 42, as at the pivot points 43, is a similarly constructed two-armed movable jaw 44. This jaw is adapted 25 to be rocked or pivoted from the open full-line position of Figure 1 into the closed full-line position of Figure 2, and this is accomplished by a pair of control rods 45 which are slidably accommodated in the guide tubes 41 and are pivoted 30 at their forward ends to the rear of the movable jaw 44, as at the pivot points 46. These rods extend rearwardly through the tubes 41, thence through suitably prepared bores in the plug 25 and are secured at their rear ends to a member 35 47 which is under the control of the scissors-like control mechanism 48.

The fixed handle of the latter mechanism is rigidly secured, as at 49, to the plug 25, and the movable handle is pivoted, as at 50, to the fixed 40 handle and has its free end pivotally articulated, as at 51, to the member 47. When the handles 48 are drawn toward each other, the member 47 is advanced forwardly, and this advances the control rods 45 and forces the movable jaw 44 45 into its closed position. When the handles 48 are separated by a slight degree, the rods 45 are correspondingly retracted, and the movable jaw is opened into the dot-and-dash position of Figure 2.

50 The electrode member shown in association with the instrument of Figures 1—5 is illustrated most clearly in Figure 7, and comprises the elongated conductive member 52 and the electrode wire 53. The latter is pivoted, as at 54, to the forward end of the conductive member 52, and is in electrical connection with the member 52. The latter is provided with a sheath of insulation 55 terminating short of the pivot point 54 and short of the rear end of the member 52; 60 and the insulation 55 is in turn ensheathed in a metallic outer sheath 56.

The electrode wire 53 is, in the form of Figure 7, provided with the offset portion 57 which doubles back upon itself at its forward end to 65 provide the journal piece 58 arranged substantially along a line passing through the pivot point 54.

70 When the electrode of Figure 7 is associated with the instrument of Figure 1, it is slid rearwardly through the guide tube or channel 40; its rear end is suitably clamped so as to bring the uninsulated rear end of the conductive member 52 in electrical connection with the binding post 75.

37, and the forward journal piece 58 is suitably articulated to the movable jaw 44.

The articulation of the journal piece 58 with the jaw 44 may be accomplished in the manner illustrated most clearly in Figures 1 and 2, and preferably consists in providing a longitudinal bearing 59 between the arms of the jaw 44, so that the journal piece 58 may be slidably inserted rearwardly into the bearing 59, as illustrated most clearly in Figure 2. This bearing is provided with an insulating lining 60 so that the electrode wire 53 is insulated from the jaw 44 and from the other portions of the instrument which are in electrical connection with the jaw 44.

The engagement of the rear end of the electrode is accomplished in the manner most clearly illustrated in Figures 2, 3, and 5, and consists in providing a suitable chuck in association with the block 35. This chuck preferably consists of the two opposed chuck jaws 61 mounted upon a threaded stud 62 which extends through the block 35. A rotatable threaded handle member 63 is mounted upon the stud 62 and may be tightened or loosened, as desired, for the purpose of clamping the jaws 61 together or separating them sufficiently to release them from the rear portion of the electrode member.

Embedded in the block 35 is a conductive element 64, and this element is provided with a longitudinal bore adapted to receive the rear uninsulated end of the conductive member 52. The interior portion 65 of the binding post 37 is in electrical connection with the element 64.

By virtue of the insulated nature of the block 35, the exterior of the binding post 37, and the sheath 55, it is obvious that by inserting the electrode member in the manner hereinbefore described the operative portion 57 of the electrode wire 53 is brought into electrical connection with the interior portion of the binding post 37, and is at the same time thoroughly and completely insulated from all portions of the instrument.

When the electrode member is clamped into association with the instrument, as described, the electrode wire 53 is effectually mounted in pivotal association, at its rear end, with the stem 38. This effect is most clearly shown in Figure 2, where it will be noted that the electrode wire 53 is adapted to pivot around the point 54 from the full-line position into the dot-and-dash-line position.

The member 47 is provided with a suitable channel in its upper portion to permit passage of the telescope 30, and with a similar suitable opening in its lower portion to permit passage of the electrode member of Figure 7. The plug 25 is also provided with a suitable bore to permit the electrode member to pass therethrough.

The capabilities of the instrument, so far as adjustability and movability of parts is concerned, will be clear from the description given. The movable jaw 44 constitutes a movable member 65 which is pivoted at its rear end to the forward portion of the stem so as to be capable of pivotal adjustment into different positions of varying obliquity with respect to the stem axis. The electrode wire 53 is pivotally associated at its rear end with the stem 38, at a point to the rear of the movable member or jaw 44. The forward or free end of the electrode wire is slidably articulated with the movable member 44. As a result, pivotal movements of the member 44 will compel similar 75 and corresponding movements of the electrode

wire 53; and during any pivotal movement of this character the operative portion 57 of the electrode wire will remain in substantially parallel relationship with the jaw 44, as indicated most clearly in Figure 2.

It is to be noted that the type of electrode illustrated in Figure 7 is one in which the electrode wire has a portion (57) projecting forwardly through the arms of the movable jaw member 44.

One manner of utilizing the instrument is illustrated in Figures 9-12. The procedure illustrated in these figures consists in electro-surgically coagulating and cutting through a growth, such as an adhesion band 66. The band 15 is first engaged as illustrated in Figures 9 and 10, at the area at which the severance is to take place. The engagement is effected between the fixed jaw 42 and the electrode wire 57. This may be accomplished under illuminated vision, 20 as will be readily understood. The engaged or clamped area is then subjected to electric coagulation by passing a suitable high-frequency coagulating current through the engaged body 66 from the electrode 53 to the electrode jaw 25 42.

One way of accomplishing this is to establish an electrical connection at the binding post 26 with one terminal of a source of suitable high-frequency coagulating current, and by establishing another connection at the binding post 30 37 with the other terminal of such current source. The coagulating current flows from the area of contact of the electrode wire 57 with the body 66, through the body 66, to both arms of the jaw 42. This efficiently and reliably coagulates the body 66 at and adjacent to the area at which it is to be cut through.

The actual cutting through or severance of the body 66 is accomplished by then utilizing the electrode wire 53 as a cutting electrode. This 40 is easily accomplished by connecting the active terminal of a suitable cutting current with the binding post 37, and connecting the other indifferent terminal of the current with the binding post 26. Obviously, the connections previously established for coagulating purposes may be retained, and suitable alterations or adjustments made in the source of high-frequency current.

With the passage of a cutting current from 50 the relatively attenuated electrode 57 to the blunter indifferent electrode 42, a cutting effect will be achieved and the electrode 57 may be advanced through the body 66 as the cutting proceeds. During this advance, and during the cutting procedure itself, the movable jaw 44 enters into a clamping relationship with respect to the fixed jaw 42, as illustrated most clearly in Figures 11 and 12, as a result of which the two resultant stumps are held in firm engagement between the opposite pairs of jaw arms. After the cut has been accomplished, the parts will be in the relationship of Figure 12, and it is to be noted that the opposed stumps are as yet unreleased by the instrument and are, therefore, still available for careful unhurried inspection by the operator. Should he find that they are not fully hemostatic, he may proceed to treat them accordingly so that he may be fully satisfied that no hemorrhage of any character is likely to 60 follow after they are finally released.

Obviously, the procedure of Figures 9-12 may be carried out without necessarily accomplishing the preliminary coagulation of the area in the manner described. Whether this preliminary co- 75

agulation is effected or not, the desirable clamping of the opposed stumps, simultaneously with the procedure of the cutting operation, is accomplished.

5 Where the preliminary coagulating procedure is not employed, the jaws 42 and 44 need not necessarily be employed as the indifferent electrode for the cutting current, and the more conventional type of remote indifferent electrode may 10 be used, if desired. In such an event, the jaws 42 and 44 serve the purely mechanical function of engaging the opposed resultant stumps as the cutting is accomplished. It is preferable, however, to employ these jaws as the indifferent electrode inasmuch as the mode of procedure is 15 greatly simplified and rendered more efficient by doing so.

It will be understood that the mode of procedure illustrated in Figures 9-12, while it constitutes by itself an important objective and phase of our present invention, and consists of a novel and improved method of severing through a mass of tissue with a maximum of safety and reliability, nevertheless the instrument of Figures 1-5 is not necessarily restricted in its uses to a procedure of this specific character. The instrument may, for example, be used for purely coagulation purposes. Or it may be used for cutting through a neoplasm or growth which is 20 not in the form of an adhesion. In the latter eventuality, the resultant stump of the growth will be engaged by one pair of opposed jaw arms, while the excised mass will be engaged by the opposite pair of opposed jaw arms. By slightly 25 releasing the jaws, the stump may be released, without at the same time releasing the excised mass; and after the stump has been released the jaws may be clamped together again to obtain a firm grasp of the excised mass, whereupon 30 the latter may be withdrawn from the interior of the body by means of these two jaws, the latter serving merely as mechanical forceps during this step.

In a similar way, the instrument may be used 35 for a variety of similar purposes, and the jaws may be employed, wherever necessary or desired, as purely mechanical forceps to engage or grasp such excised masses or pieces of tissue as may be necessary to accomplish any specific objective, depending upon circumstances.

In Figure 8, we have illustrated a modified type of electrode which may be associated with the instrument in place of the electrode illustrated in Figure 7. This electrode consists of a conductive elongated member 70, ensheathed in a tube of insulation 71, and an outer metallic sheath 72. The rear and forward ends of the member 70 are exposed, as before, and at the forward end is a pivot 73 to which the rear of an electrode 74 is pivotally attached. The electrode is, in this case, constructed in a manner whereby it will always lie to the rear of the movable member 44; and with this object in view, the electrode is provided with the offset forward 60 journal piece 75.

This electrode is inserted into the instrument in the same manner as the previously described electrode, being snugly accommodated within the guide tube 40 and having its rear end 70 in electrical contact with the conductive element 65. The forward journal piece 75 is mounted in slideable association with the bearing 59, but in this case the journal piece projects forwardly into the bearing, while in the previous case the journal piece 75 projected rearwardly into the bearing.

The relationship of parts, when this assembly has been effected, is shown most clearly in Figures 6, 13, and 14, and it will be observed that pivotal movements of the member 44 into varied positions of obliquity will compel similar and responsive movements of the electrode wire 74.

The ease with which the parts may thus be adjusted into any desired oblique position permits the instrument to be used for a wide variety of purposes, one of which is shown, merely by way of illustration, in Figures 13 and 14. The reference numeral 76 is applied to a protrusion at the interior end of a body canal 77, and it will be observed that when the instrument is adjusted into the position of Figure 13 the electrode wire 74 is admirably situated for performing any desired act of electro-surgical treatment upon the remote wall of the protrusion 76. This remote wall is usually difficult of access, but the present instrument permits the wire 74 to be brought into efficient contact therewith. If the protrusion is to be treated further, as, for example, along the upper edge or area thereof, it is a relatively simple matter to adjust the electrode wire 74 into the position of Figure 14, in which event further desired contact may be established at any required area.

The actual procedure which it may be desired to carry out in any given case will depend, of course, upon the circumstances of that case; but we will mention, in passing, that the procedure illustrated in Figures 13 and 14 may, for example, be one of pure coagulation of tissue, or of other diathermic treatment, shrinkage, or destruction of tissue. The adjustability of the parts permits the instrument to be used with great ease under a variety of specialized conditions.

The electrode 74 may also be used for cutting purposes, and we have found that the instrument of Figures 6, 13, and 14 is admirably suited for effecting excision of growths or masses that are inconveniently located in places which would otherwise be difficult of access. Whenever a cutting is accomplished with this electrode, the movable member 44 serves as a convenient "stop" or abutment which limits the depth of cutting.

When the electrode 74 is used as a cutting electrode a suitable connection must be made to an indifferent electrode; and, if desired, the endoscopic tube 20, if composed of metal, may be used for this purpose, thereby permitting the binding post 26 to be employed as a convenient point of connection for the indifferent terminal.

The forcep jaws 42 and 44 are obviously available, as before, for purposes of grasping any excised masses or the like, after any particular cutting operation has been consummated.

It will be obvious that other electrodes, of varying configurations, depending upon the particular uses to which they are to be put, may be employed with the present instrument, and that the electrodes of Figures 7 and 8 have been illustrated merely by way of example and for the purpose of explaining the general nature and capabilities of our present instrument. The essential characteristics of any electrode of the present character are that it consist of an elongated conductive member adapted to be clamped at the rear, in association with the terminal block 35, together with an electrode wire or the like pivotally connected to the forward end of the conductive member. The electrode wire must embody a journal piece which may be slidably engaged with the bearing 59.

All of the foregoing procedures are, of course,

capable of accomplishment under illuminated vision, as will be obvious from the arrangement and construction of the telescope illustratively shown in the present drawings. The formation

5 of the jaws 42 and 44 with two spaced parallel arms permits unimpeded vision of the electrode wire and of the area which is the subject of treatment or engagement. The irrigation outlet 23 may be conveniently employed as an aspirating 10 outlet for drawing fumes rearwardly through the instrument and hence out of the path of the objective of the telescope.

Under certain circumstances, we contemplate 15 eliminating one of the control arms 45 (since one alone would be sufficient to effect the desired movements of the jaw 44), and utilizing the empty guide tube 41 for purposes of irrigation, either liquid or gaseous.

It will be observed that from certain aspects 20 the stationary jaw is not always essential. That is, in so far as the movability and adjustability of the electrode wire is concerned, the movable jaw 44 is in itself a sufficient instrumentality for effecting the desired pivotal movements.

25 From another aspect, it will be obvious, from the descriptions given, that the jaws need not necessarily be employed as electrode jaws, but that their use as an electrode is highly desirable and advantageous under many conditions, 30 as hereinbefore described.

It will also be understood that the uses to 35 which the instrument may be put are of a varied character, and we do not intend to limit the instrument to the specific uses hereinbefore described by way of illustration. It may be stated, briefly, that the instrument has proven to be highly satisfactory in the treatment and severance of adhesions generally, both pulmonary and abdominal; in the treatment and removal of 40 growths and protrusions in the rectum, lower bowels, trachea, bronchi, and oesophagus; and in the general treatment, cutting, and excision of a variety of neoplastic and papillomatous growths and masses.

45 In general, it will be understood that changes in the details herein described and illustrated for the purpose of explaining the nature of our invention may be made by those skilled in the art, without departing from the spirit and scope of the invention as expressed in the appended claims. It is therefore intended that these details be interpreted as illustrative, and not in a limiting sense.

Having thus described our invention, and illustrated its use, what we claim as new and desire to secure by Letters Patent is—

1. In an instrument of the character described, an elongated stem, a member pivotally mounted at its rear end to the forward portion of the stem 60 so as to be movable from a longitudinal position into positions of varying obliquity with respect to the stem axis, a longitudinal electrode whose rear end is pivotally associated with the stem rearwardly of said member, and means articulating said member and electrode for constraining the electrode to move with and substantially parallel to said member.

2. In an instrument of the character described, an elongated stem, a member pivotally mounted 70 at its rear end to the forward portion of the stem so as to be movable from a longitudinal position into positions of varying obliquity with respect to the stem axis, a longitudinal electrode whose rear end is pivotally associated with the stem rearwardly of said member, and means

carried by said member and articulated to the forward portion of said electrode for compelling the latter to respond in its pivotal movements to the pivotal movements of said member.

3. In an instrument of the character described, 5 an elongated stem, a member pivotally mounted at its rear end to the forward portion of the stem so as to be movable from a longitudinal position into positions of varying obliquity with respect to the stem axis, a longitudinal electrode 10 whose rear end is pivotally associated with the stem rearwardly of said member, and means slidably articulating the forward portions of said member and electrode so that pivotal movements of said member will effect corresponding pivotal movements of said electrode.

4. In an instrument of the character described, 15 an elongated stem, a member pivotally mounted at its rear end to the forward portion of the stem so as to be movable from a longitudinal position into positions of varying obliquity with respect to the stem axis, a longitudinal bearing carried by said member, a longitudinal electrode whose rear end is pivotally associated with the stem rearwardly of said member, and a journal 20 piece at the forward end of said electrode and slidably accommodated in said bearing.

5. In an instrument of the character described, 25 an elongated stem, a member comprising parallel arms and pivotally mounted at the rear ends of said arms to the forward portion of said stem, mechanism for pivoting said member from a longitudinal position into positions of varying obliquity with respect to the stem axis, a longitudinal electrode lying in a plane between said 30 arms and having its rear end pivotally associated with the stem rearwardly of said member, and means articulating said member and electrode for constraining the electrode to pivot in said plane when said member is pivotally moved.

6. In an instrument of the character described, 35 an elongated stem, a member comprising parallel arms and pivotally mounted at the rear ends of said arms to the forward portion of said stem, mechanism for pivoting said member from a longitudinal position into positions of varying obliquity with respect to the stem axis, a longitudinal electrode lying in a plane between said arms and having its rear end pivotally associated with the stem rearwardly of said member, and means lying 40 between said arms and slidably articulating the latter to the forward portion of said electrode so that pivotal movements of said member will effect corresponding pivotal movements of said electrode in said plane.

7. In an instrument of the character described, 45 an elongated stem, a member comprising parallel arms and pivotally mounted at the rear ends of said arms to the forward portion of said stem, mechanism for pivoting said member from a longitudinal position into positions of varying obliquity with respect to the stem axis, a longitudinal bearing carried by said member between the forward portions of said arms, a longitudinal electrode lying in a plane between said arms and having 50 its rear end pivotally associated with the stem rearwardly of said member, and a journal piece 55 at the forward end of said electrode and slidably accommodated in said bearing.

8. In an instrument of the character described, 60 an elongated stem, a member comprising parallel arms and pivotally mounted at the rear ends of said arms to the forward portion of said stem, mechanism for pivoting said member from a longitudinal position into positions of varying obliquity 65 with respect to the stem axis, a longitudinal electrode whose rear end is pivotally associated with the stem rearwardly of said member, and means 70 slidably articulating the forward portions of said member and electrode so that pivotal movements of said member will effect corresponding pivotal movements of said electrode.

- uity with respect to the stem axis, a longitudinal electrode lying in a plane between said arms and having its rear end pivotally associated with the stem rearwardly of said member, said electrode having a portion projecting forwardly through the space between said arms, and means carried by said arms and articulated to the forward portion of said electrode for compelling the latter to respond in its pivotal movements to the pivotal movements of said member.
19. In an instrument of the character described, an elongated stem, a member pivotally mounted at its rear end to the forward portion of the stem so as to be movable from a longitudinal position into positions of varying obliquity with respect to the stem axis, a longitudinal electrode whose rear end is pivotally associated with the stem rearwardly of said member, means articulating said member and electrode for constraining the electrode to pivot under the influence of corresponding pivotal movements of said member, an electric binding post mounted in insulated relationship at the rear of said stem, insulated means for electrically connecting said binding post with said electrode, and means for insulating said electrode from said member at said articulation.
20. In an instrument of the character described, an elongated stem, a member pivotally mounted at its rear end to the forward portion of the stem so as to be movable from a longitudinal position into positions of varying obliquity with respect to the stem axis, a longitudinal bearing carried by said member, a longitudinal electrode whose rear end is pivotally associated with the stem rearwardly of said member, an electric binding post mounted in insulated relationship at the rear of said stem, insulated means for electrically connecting said binding post with said electrode, a journal piece at the forward end of said electrode and slidably accommodated in said bearing, and means for insulating said journal piece from said bearing.
21. In an instrument of the character described, an elongated stem, a stationary electrode jaw longitudinally arranged at the forward end of said stem, a member pivotally mounted at its rear end to the rear end of said jaw so as to be pivotable toward and away from the latter, a longitudinal electrode wire whose rear end is pivotally associated with the stem rearwardly of said jaw, said electrode wire having a portion projecting forwardly of said member, means slidably articulating the forward portions of said member and electrode wire so that pivotal movements of said member will effect corresponding pivotal movements of said electrode wire, and means for insulating said wire from said jaw so that said jaw and wire may serve as opposite electrodes for directing an electric current through a body clamped between them.
22. In an instrument of the character described, an elongated stem, a stationary jaw longitudinally arranged at the forward end of said stem, a complementary jaw pivotally mounted at its rear end to the rear end of said stationary jaw so as to be pivotable toward and away from the latter, and a longitudinal electrode wire articulated to and insulated from said movable jaw so as to be pivotable with the latter, whereby movement of the electrode toward the stationary jaw is automatically coupled with a pivotal closing motion of said complementary jaws.
23. In an instrument of the character described, an elongated stem, a stationary jaw longitudinally arranged at the forward end of said stem, a complementary jaw pivotally mounted at its rear end to the rear end of said stationary jaw so as to be pivotable toward and away from the latter, a longitudinal electrode wire articulated to and insulated from said movable jaw so as to be pivotable with the latter, whereby movement of the electrode toward the stationary jaw is automatically coupled with a pivotal closing motion of said complementary jaws.
24. In an instrument of the character described, an elongated stem, a stationary jaw comprising spaced parallel arms longitudinally arranged at the forward end of said stem, a complementary jaw comprising corresponding spaced parallel arms and pivotally mounted at its rear end to the rear end of said stationary jaw so as to be pivotable toward and away from the latter, a longitudinal electrode wire arranged in a plane passing between the arms of said stationary jaw and articulated to said movable jaw so as to be pivotable with the latter, means for insulating said electrode wire from said movable jaw, and mechanism for controlling the movements of said movable jaw from the rear of the stem, whereby said electrode wire may be pivoted toward the stationary jaw to act upon a body arranged between said jaws, and whereby said movement of the electrode wire is accompanied by a movement of said jaws toward a closed relation with respect to such body.
25. In an instrument of the character described, an elongated stem, a stationary jaw comprising spaced parallel arms longitudinally arranged at the forward end of said stem, a complementary jaw comprising corresponding spaced parallel arms and pivotally mounted at its rear end to the rear end of said stationary jaw so as to be pivotable toward and away from the latter, a longitudinal electrode wire arranged in a plane passing between the arms of said stationary jaw and articulated to said movable jaw so as to be pivotable with the latter, and means for insulating said electrode wire from said movable jaw, whereby said electrode wire may be pivoted toward the stationary jaw to act upon a body arranged between said jaws, and whereby said movement of the electrode wire is accompanied by a movement of said jaws toward a closed relation with respect to spaced areas of said body on opposite sides of the line of action of said electrode wire.
26. In an instrument of the character described, an elongated stem, a stationary electrode jaw comprising spaced parallel arms longitudinally arranged at the forward end of said stem, a member pivotally mounted at its rear end to the rear end of said jaw so as to be pivotable toward and away from the latter, a longitudinal electrode wire arranged in a plane lying between said arms and having its rear end pivotally associated with the stem rearwardly of said jaw, said electrode wire having a portion projecting forwardly of said member, means slidably articulating the forward portions of said member and electrode wire so that pivotal movements of said member will effect corresponding pivotal movements of said electrode wire, and means for insulating said wire from said jaw so that said jaw and wire may serve as opposite electrodes for directing an electric current through a body clamped between them.
27. In an instrument of the character described, an elongated stem, a stationary electrode jaw comprising spaced parallel arms longitudinally arranged at the forward end of said stem, a complementary jaw comprising corresponding spaced parallel arms and pivotally mounted at its rear end in uninsulated relation to the rear end of said stationary jaw so as to be pivotable toward and away from the latter, a longitudinal electrode wire arranged in a plane passing between the arms of said jaws and slidably articulated to said movable jaw so as to be pivotable with the latter, said wire having a portion projecting forwardly through the arms of the movable jaw, and means for insulating said electrode wire from said movable jaw and hence from said stationary electrode jaw, whereby said electrode jaw and electrode wire may serve as opposite electrodes for directing an electric current through a body clamped between them, and whereby movement of the electrode wire toward the stationary jaw

is accompanied by a closing action of said jaws upon spaced areas of said body on opposite sides of the plane of movement of said electrode wire.

17. In an instrument of the character described, 5 an elongated stem, a member pivotally mounted at its rear end to the forward portion of the stem so as to be movable into positions of varying obliquity with respect to the stem axis, a longitudinal electrode wire having its rear end pivotally associated with the stem and its forward end slidably articulated to said member, and means for removably mounting said electrode wire in association with said stem and member.

18. In an instrument of the character described, 15 an elongated stem, a member pivotally mounted at its rear end to the forward portion of the stem so as to be movable into positions of varying obliquity with respect to the stem axis, a longitudinal electrode wire having its rear end pivotally associated with the stem and its forward end slidably articulated to said member, and means for removably mounting said electrode wire in association with said stem and member; 20 said means comprising a clamp at the rear of said stem, and a conductive body pivotally connected to the rear end of said wire and removably engaged at its rear end by said clamp.

19. In an instrument of the character described, 10 an elongated stem, a member pivotally mounted at its rear end to the forward portion of the stem so as to be movable into positions of varying obliquity with respect to the stem axis, a binding post mounted in insulated relation at the rear end of said stem, a conductive body arranged in insulated relation along said stem, an electrode wire pivoted to the forward end of said body, means for removably securing the rear end 10 of said body in electrical connection with said binding post, and means for removably articulating the electrode wire in insulated relation at its forward end to said member.

20. As a new article of manufacture, an electrode device for removable association with an instrument of the character described, comprising an elongated conductive body, a sheath of insulation around said body and terminating short of its rear end so that the latter may be removably clamped into electrical connection with a binding post, an uninsulated electrode wire pivoted to the forward end of said body, and a journal piece at the forward end of said electrode wire for slidably articulation with a bearing member. 25
